US0D1056806S

(12) **United States Design Patent** (10) **Patent No.:** **US D1,056,806 S**
(45) **Date of Patent:** **** Jan. 7, 2025**

(54) **TRUCK CAP**

(71) Applicant: **Leer Group**, Elkhart, IN (US)

(72) Inventors: **Jeffrey Joal Hickey**, Sturgis, MI (US);
Donald Richard Ireland, Middlebury, IN (US); **Terrill D. Becker**, Bristol, IN (US); **Mitchell Austin Westra**, Granger, IN (US); **James Dillard Fletcher**, Elkhart, IN (US)

(73) Assignee: **Leer Group**, Elkhart, IN (US)

(**) Term: **15 Years**

(21) Appl. No.: **29/883,317**

(22) Filed: **Jan. 26, 2023**

Related U.S. Application Data

(62) Division of application No. 29/711,962, filed on Nov. 4, 2019, now Pat. No. Des. 976,801.

(57) **CLAIM**

The ornamental design for a truck cap as shown and described.

DESCRIPTION

FIG. 1 is a side view of a truck cap design;

FIG. 2 is a perspective view thereof;

FIG. 3 is a rear view thereof;

FIG. 4 is a bottom perspective view thereof, shown in an alternate configuration;

FIG. 5 is a bottom perspective view thereof;

FIG. 6 is a bottom perspective exploded view thereof;

FIG. 7 is a bottom view thereof, shown in an alternative configuration; and,

FIG. 8 is another bottom perspective exploded view thereof. The broken lines shown in the drawings illustrate portions of the truck cap and forms no part of the claimed design.

1 Claim, 8 Drawing Sheets
